UNITED STATES PATENT OFFICE.

SAMUEL APPLETON, OF BRISTOL, PENNSYLVANIA.

DESIGN FOR KNITTED FABRICS.

SPECIFICATION forming part of Design No. 11,738, dated April 20, 1880.

Application filed February 6, 1880. Term of patent 3½ years.

To all whom it may concern:

Be it known that I, SAMUEL APPLETON, a citizen of the United States, residing in Bristol, in the county of Bucks and State of Pennsylvania, have invented a new and original Design for a Knitted Fabric, of which the following is a specification.

The design consists of a series of alternating stripes, A, and ribs B. The stripes A are arranged at equal distances apart from each other, and are composed of ordinary knitted fabric.

Each rib B consists of three parallel narrow stripes, b d e, the middle one of which is of the same character throughout, and is composed of threads extending diagonally in opposite directions between the stripes b and e. The colors of each of the stripes b and e, however, are changed at intervals, the change taking place where the parallel lines xx , drawn at right angles to the stripes, occur. The loops on these lines are so distinct from those composing the main stripes A as to give to the fabric a plaid-like effect, while the parti-colored stripes b and e and the stripes d impart an attractive and variegated appearance to the pattern.

The colors may, of course, be varied to suit the tastes of different purchasers.

I claim as my invention—

The within-described design for a knitted fabric, said design comprising alternating parallel stripes A and ribs B, the stripes A being composed of ordinary knitted fabric, and the ribs B comprising parti-colored stripes b and e and intervening stripes, d, formed of crossing threads, all substantially as described and shown.

In testimony whereof I have signed my name to this specification in the presence of two subscribing witnesses.

SAMUEL APPLETON.
